JAMES FORBES, OF PLAINWELL, MICHIGAN.

Letters Patent No. 69,201, dated September 24, 1867.

IMPROVEMENT IN MODE OF ATTACHING CALKS TO HORSES' SHOES.

The Schedule referred to in these Letters Patent and making part of the same.

TO ALL WHOM IT MAY CONCERN:

Be it known that I, JAMES FORBES, of Plainwell, in the county of Allegan, and State of Michigan, have invented a new and improved Mode of Attaching Horse-Shoe Calks; and I do hereby declare that the following is a full and exact description thereof, reference being had to the accompanying drawings, making part of this specification, in which—

Figure 1 is a side view of a portion of a horse-shoe with a section through the toe and one of the heel-calks.

Figure 2 is a perspective view of the toe-calk detached.

Like letters designate corresponding parts in both figures.

My invention consists in the special manner, hereinafter described, of attaching the calks to horse-shoes, so that they may be readily detached for sharpening without removing the shoe from the foot.

In the drawings, A represents the shoe, B the toe, and C one of the heel-calks. These calks are provided with hooks or beaks *e* (preferably two for the toe, one being sufficient for each heel-calk,) on their upper face, or the side in contact with the shoe. The under side of the shoe is provided with corresponding sockets for the reception of these beaks. The calks are also provided with a flange extension, *f*, which is secured to the shoe by means of a screw, *g*, as shown. The beaks are hooked, and incline, preferably, forward, as represented, so that when the animal is drawing, the tendency will be to press the hook more firmly in its socket, the beaked end of which holds it firmly to the shoe, thereby relieving the screw in a great measure of the strain that would otherwise come upon it. Thus the beaks serve the double purpose of preventing lateral displacement and the separation of the calks from the shoe. Were it not for the latter function, which is due to the hooked form of the projections, it would be extremely difficult, if not impossible, to keep the calk secure by a screw alone, as the great strain to which it would be subject would soon wear or tear off the thread, and thus unloose the calk.

My improvement enables the calks to be readily detached from the shoe, and sharpened, without removing the latter, which, to farmers and others living at a distance from a smith's shop, is a matter of considerable importance, and especially so in winter, when it often is necessary to sharpen the calks every few days.

What I claim as my invention, and desire to secure by Letters Patent, is—

Attaching the calks to horse-shoes by means of the hook or beak *e* and screw *f*, in the manner and for the purpose set forth.

In witness whereof I have hereunto signed my name in the presence of two subscribing witnesses.

JAMES FORBES.
